US00D889035S

(12) **United States Design Patent** (10) **Patent No.:** **US D889,035 S**
(45) **Date of Patent:** ** *Jun. 30, 2020

(54) **CASE**

(71) Applicant: **JUUL Labs, Inc.**, San Francisco, CA (US)

(72) Inventors: **Brandon Cheung**, San Francisco, CA (US); **Richard Johnson**, San Francisco, CA (US); **Kevin Lomeli**, San Francisco, CA (US); **James Monsees**, San Francisco, CA (US); **Alexander Ringrose**, Oakland, CA (US); **Roxolana Wacyk**, San Francisco, CA (US)

(73) Assignee: **JUUL Labs, Inc.**, San Francisco, CA (US)

(*) Notice: This patent is subject to a terminal disclaimer.

(**) Term: **15 Years**

(21) Appl. No.: **29/635,088**

(22) Filed: **Jan. 26, 2018**

(51) LOC (12) Cl. **27-06**

(52) U.S. Cl.

USPC **D27/186**

(58) **Field of Classification Search**

USPC ..... D27/100, 101, 139–161, 162–196; D23/366; D24/110; D19/101, 106, 115, D19/165, 195; D7/416; D3/212, 247 CPC A24F 47/00; A24F 47/002; A24F 15/12; A24F 1/32; A24F 15/18

(57) **CLAIM**

The ornamental design for a case, as shown and described.

DESCRIPTION

FIG. 1 is a front, top, and right side perspective view of a case showing our new design;

FIG. 2 is a rear, top, and right side perspective view thereof;

FIG. 3 is a right side view thereof;

FIG. 4 is left side view thereof;

FIG. 5 is a front view thereof;

FIG. 6 is a rear view thereof;

FIG. 7 is a top view thereof; and,

FIG. 8 is a bottom view thereof.

The dash-dash broken lines illustrate portions of the case that form no part of the claimed design.

1 Claim, 8 Drawing Sheets
